Primary Examiner — Robert M Spear*Assistant Examiner* — Marissa J Cash(74) *Attorney, Agent, or Firm* — McDonnell Boehnen Hulbert & Berghoff LLP(57) **CLAIM**

The ornamental design for a dispenser for e-liquid, as shown and described.

DESCRIPTION

FIG. 1 is a perspective view of a first embodiment of a dispenser for e-liquid of the present design;

FIG. 2 is a front view thereof;

FIG. 3 is a rear view thereof;

FIG. 4 is a top view thereof;

FIG. 5 is a bottom view thereof;

FIG. 6 is left side view thereof;

FIG. 7 is right side view thereof;

FIG. 8 is a perspective view of a second embodiment of a dispenser for e-liquid of the present design;

FIG. 9 is a front view thereof;

FIG. 10 is a rear view thereof;

FIG. 11 is a top view thereof;

FIG. 12 is a bottom view thereof;

FIG. 13 is left side view thereof; and,

FIG. 14 is right side view thereof.
